(57) **CLAIM**

The ornamental design for a laryngoscope, as shown and described.

DESCRIPTION

FIG. 1 is a perspective view of a laryngoscope.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a top plan view thereof.

FIG. 7 is a bottom plan view thereof.

FIG. 8 is a right side elevational view of the laryngoscope of FIG. 1 shown in a closed position; and,

FIG. 9 is a rear elevational view in a closed position.

The broken lines depict portions of the laryngoscope that form no part of the claimed design. The dash dot broken lines show the boundary of the claim and form no part of the claimed design.
